GOLF CLUB

George Adrian Phillips, Milwaukee, Wis.

Application March 14, 1957, Serial No. 45,255

Term of patent 14 years

(Cl. D34—5)

Fig. 1 is a side view in elevation showing my new design for a golf club.

Fig. 2 is a plan view of the club head.

Fig. 3 is an inverted plan view thereof.

Fig. 4 is a front face view.

Fig. 5 is a side view opposed to Fig. 1.

Fig. 6 is a cross-sectional view taken on line 6—6 of Fig. 5.

Fig. 7 is a similar view taken on line 7—7 of Fig. 2.

The essential features of my design reside in the club head shown in full lines on the drawing.

I claim:

The ornamental design for a golf club, as shown and described.
